CLAIM

The ornamental design for walk-through sanitizing device, as shown and described.

DESCRIPTION

FIG. 1 is a front, top and right perspective view of a walk-through sanitizing device, showing our new design;

FIG. 2 is a right side elevation view thereof;

FIG. 3 is a left side elevation view thereof;

FIG. 4 is a front elevation view thereof;

FIG. 5 is a rear elevation view thereof;

FIG. 6 is a top plan view thereof;

FIG. 7 is a bottom plan view thereof;

FIG. 8 is a front, top and right perspective of a second embodiment of walk-through sanitizing device, showing our new design;

FIG. 9 is a right side elevation view thereof;

FIG. 10 is a left side elevation view thereof;

FIG. 11 is a front elevation view thereof;

FIG. 12 is a rear elevation view thereof;

FIG. 13 is a top plan view thereof; and,

FIG. 14 is a bottom plan view thereof.

The broken line portions show unclaimed subject matter only and form not part of the claimed design.

1 Claim, 12 Drawing Sheets
